UNITED STATES PATENT OFFICE

91,457

DESIGN FOR AN ARTILLERY WHEEL

Warren H. Farr and Carolus L. Eksergian, Detroit, Mich., assignors to Budd Wheel Company, Philadelphia, Pa., a corporation of Pennsylvania

Application November 17, 1933. Serial No. 49,772

Term of patent 14 years

To all whom it may concern:

Be it known that we, WARREN H. FARR and CAROLUS L. EKSERGIAN, citizens of the United States, residing at Detroit, in the county of Wayne and State of Michigan, have invented a new, original, and ornamental Design for an Artillery Wheel, of which the following is a specification, reference being had to the accompanying drawing which forms a part hereof.

Figure 1 is a perspective of our new wheel design.

Figure 2 is an enlarged fragmentary side elevation.

Figure 3 is an axial profile, and

Figure 4 is a transverse spoke section.

We claim:

The ornamental design for an artillery wheel as shown.

Signed at Detroit, county of Wayne, State of Michigan, this 15 day of November, 1933.

WARREN H. FARR.
CAROLUS L. EKSERGIAN.
